UNITED STATES PATENT OFFICE.

ABNER JOHNSON, OF ROCKFORD, ILLINOIS.

DESIGN FOR A HOOK.

SPECIFICATION forming part of Design No. 24,406, dated June 18, 1895.

Application filed May 16, 1895. Serial No. 549,457. Term of patent 14 years.

To all whom it may concern:

Be it known that I, ABNER JOHNSON, a citizen of the United States, residing at Rockford, in the county of Winnebago and State of Illinois, have invented and produced a new and original Design for Hooks for Staging-Brackets, of which the following is a specification, reference being had to the accompanying drawing, forming a part thereof.

The nature of my design is fully illustrated in the accompanying drawing, to which reference is made.

The leading features of my design consist of the hook A terminating in the shank B provided with the transverse stay bar C. 15

What I claim is—

The design for a hook for staging brackets, substantially as herein shown and described.

ABNER JOHNSON.
